UNITED STATES PATENT OFFICE.

GEORGE A. BERRY, OF MODESTO, CALIFORNIA.

TRUSS.

Application filed May 19, 1921. Serial No. 470,966.

To all whom it may concern:

Be it known that I, GEORGE A. BERRY, a citizen of the United States, and a resident of Modesto, in the county of Stanislaus and 5 State of California, have invented a new and Improved Truss, of which the following is a description.

My invention relates to a truss for hernia and has for its general object to provide a 10 construction that will result in the truss being firmly maintained against displacement when applied and that will afford the minimum discomfort and rubbing action on the wearer.

15 The nature of the invention, its advantages and its distinctive features will clearly appear as the description proceeds.

Reference is to be had to the accompanying drawings forming a part of this specification, it being understood that the drawings are merely illustrative of one example 20 of the invention.

Figure 1 is a rear view of a truss embodying my invention, the usual belt being omitted;

Figure 2 is a top view;

Figure 3 is a transverse vertical section taken at the medial line of the truss;

Figure 4 is a section taken longitudinally 30 through one of the hernia pads;

Figure 5 is a front perspective view of the complete truss including the belt.

In carrying out my invention in accordance with the illustrated example, I provide an element 10 which in the preferred 35 form of the invention consists of a stiff plate spring, but when used with an elastic belt said element 10 may be rigid instead of resilient. To the rear face of said element is secured a pressure plate 11 adapted to be 40 presented to the body of the wearer, said plate being fastened, in any suitable manner, approximately centrally to the spring 10 at or adjacent to the medial line, there being 45 indicated fastening screws 12, in vertical alinement. The plate 11 presents a broad surface. On the plate 11 at the lower portion is a pair of pads 13 positioned at opposite sides of the vertical medial line of said 50 plate and disposed oblique to said medial line. Advantageously the pads 13 are secured to lateral extensions 11^a of the plate 11, said plate being contracted adjacent to said pads and extensions and broadened substantially above the contraction. The formation 55 of the plate 11 is such that the exten-

sions 11^a and the pads 13 thereon are in planes at angles to each other, said extensions being deflected rearwardly. Briefly, the pads 13 are oblique to a vertical line 60 and in intersecting planes to flare rearwardly relatively to each other. In addition to the deflection and rearward flare of the extensions 11^a of the plate 11, said plate advantageously is curved vertically and transversely, the upper portion of the plate being deflected into the planes of the pads 13. 65

The plate spring 10 has means to fasten it to the ends of a belt 15 there being shown hooks 14 provided in pairs and directed laterally inward at the ends of the plate for receiving bends 16^a in wire loops 16 on the ends of the belt 15, it being understood that any other approved co-engaging fastening means may be provided on the belt 15 and 70 spring 10.

The spring 10 is curved longitudinally to present a convex curvature at the front as clearly seen in Figure 2 so that the tightening of the belt will tend to straighten said 80 spring 10 and stress the same that the tension of the spring may be effectively exerted on the plate 11 to thereby firmly maintain the plate 11 and pads 13 against the wearer but without severity notwithstanding the 85 stiff character of the plate and the fixed relation of the pads 13 and plate.

The pads 13 are made adjustable in their own planes and relatively to each other and to the plate 11 for the purpose of giving 90 them a greater range of efficiency in locating them over the crucial points of the body for effective pressure at the hernia. In the illustrated example I have shown as a means for the stated purpose a pair of 95 screws 17 for each pad and to receive the screws a plurality of holes are provided to be selectively employed according to the adjustment desired. Three holes 17^a are shown in the illustrated form extending through the spring 10 and each extension 11^a and five holes 17^b are shown in the pad 13 at the back in Figure 4, any pair of which may be alined with any two of the holes 17^a. The arrangement is such that with the screws 17 and holes 17^a a limited 100 longitudinal adjustment of the pad may be effected in the plane of the pad and a wider range of adjustment by the screw 17 and a selected pair of holes 17^b. 105

The plate 11 by reason of the described 110 formation will exert a pressure on a body

of the wearer above the pads 13 in that said pads will give result in points or areas of pressure in triangular relation. The general pressure is very effectively applied by 5 reason of the plate 10 being stressed by the tightening of the belt 15.

I would state in conclusion that while the illustrated example constitutes a practical embodiment of my invention, I do not limit 10 myself strictly to the mechanical details herein illustrated, since manifestly the same can be considerably varied without departure from the spirit of the invention as defined in the appended claims.

15 Having thus described my invention, I claim:

1. A truss including a stiff broad pressure plate presenting a permanent concave curvature at the back thereof, pads on said plate 20 at the back thereof adjacent to the lower edge and disposed in planes at an angle to each other, said plate being permanently deflected rearwardly at the top portion into the vertical planes of the pads, and a stiff 25 elongated plate spring secured at its approximate center to said pressure plate and extending beyond the side edges of said plate, said spring being curved longitudinally to present a concave curvature at the 30 front, and having belt securing means adjacent to its ends, to adapt the spring to be stressed by the tightening of the belt on the wearer to thereby exert spring pressure against the plate for maintaining the plate 35 and pads against displacement when the truss is worn.

2. A truss including a stiff broad pressure plate presenting a concave curvature at the back thereof, pads on said plate at the back 40 thereof adjacent to the lower edge at each side of the medial line and disposed in planes at an angle to each other, said plate being permanently deflected rearwardly at the top portion to overhang the pads, and 45 an elongated carrying element secured at its approximate center to said pressure plate and extending beyond the side edges thereof and provided with belt-securing means.

3. A truss including a plate substantially 50 oval in shape and presenting adjacent the

lower end a pair of rearwardly deflected projections, pads adjustably secured to said projections, said plate being permanently deflected at its upper end to overhang said pads and a spring elongated member secured 55 to said plate adjacent its center for carrying the same, said member being adapted to straighten in its normal plane and thereby causing said plate and pads to resiliently bear against the body of the wearer.

4. A truss including a carrying element, a broad stiff pressure plate secured at its medial line to said element, at the approximate center of the latter, and pads on the plate, said pads being disposed at opposite 60 sides of the medial line and oblique to the latter in planes at an angle to each other, said pressure plate being curved transversely and vertically so that its upper portion is deflected to overhang said pads.

5. A truss including a carrying element, a broad stiff pressure plate secured at its medial line to said element at the approximate center of the latter, and pads on the plate, said pads being disposed at opposite 70 sides of the medial line and oblique to the latter in planes at an angle to each other, said plate being deflected rearwardly at its upper portion to overhang said pads.

6. A truss including a plate spring, a broad stiff pressure plate secured at its medial line to the spring at the approximate center of the latter, and pads on the plate, said pads being disposed at opposite 80 sides of the medial line and oblique to the latter in planes at an angle to each other, said pressure plate being curved transversely and vertically so that its upper portion is deflected to overhang said pads.

7. A truss including a plate spring, a broad stiff pressure plate secured at its medial line to the spring at the approximate center of the latter, and pads on the plate, said pads being disposed at opposite 90 sides of the medial line and oblique to the latter in planes at an angle to each other, said plate being deflected rearwardly at its upper portion to overhang the said pads.

GEORGE A. BERRY.
